(57) **CLAIM**

The ornamental design for a manipulator for robot, as shown and described.

DESCRIPTION

FIG. 1 is a rear perspective view of the rear, right, and top sides of a manipulator for robot showing a first embodiment of our new design;

FIG. 2 is a front perspective view of the front, right, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front side view showing a state where a hinge angle is changed;

FIG. 10 is a right side view showing a state where a hinge angle is changed;

FIG. 11 is a front perspective view of the front, right, and bottom sides of a manipulator for robot showing a second embodiment of our new design;

FIG. 12 is a rear perspective view of the rear, right, and top sides thereof;

FIG. 13 is a front view thereof;

FIG. 14 is a rear view thereof;

FIG. 15 is a left side view thereof;

FIG. 16 is a right side view thereof;

FIG. 17 is a top plan view thereof;

FIG. 18 is a bottom plan view thereof; and,

FIG. 19 is a front side view showing a state where a hinge angle is changed.

The broken lines shown represent unclaimed subject matter of the manipulator for robot or environments and form no part of the claimed design.
